New York, N. Y., a corporation of New
York

Application April 25, 1935, Serial No. 18,145

4 Claims. (Cl. 235—61.7)

This invention relates to accounting machines and more particularly to automatic group control systems for record controlled tabulators. Record controlled tabulators are designed to add, 5 list, and print totals of items automatically entered in the machine from control records on which the items are represented by index point perforations located in different positions in the several card columns, each column ordinarily 10 representing one character which may be either a number or a letter.

The cards are fed through the machine automatically and analyzed by suitable mechanism, which in turn controls the accumulating and 15 printing devices of the machine so that the data represented by the perforations in the card may be accumulated and printed.

The controlling records are usually divided into groups representing different classifications, 20 the group classification being represented in each card by similarly located perforations and it is desirable to continue the automatic feeding of the records to the analyzing mechanism as long as the group classification does not change 25 but to interrupt the card feed for the purpose of taking totals or performing other operations when the group changes. This is ordinarily accomplished by providing two sets of analyzing brushes which are spaced apart so that one card 30 feeds to one of them as the preceding card feeds to the other and so that the same index point positions on successive cards are under the analyzing mechanisms simultaneously.

Tabulators, which analyze and control with 35 the records in motion, are ordinarily of the electrical type and the analyzing mechanism consists of a contact roller cooperating with individual brushes. The cards are fed between the roller and the brushes to hold an electric circuit 40 open for each card column as long as there are no perforations in such column on the card but to permit engagement of each brush with the roller through the card when the brush encounters a perforation on the card. In machines of 45 the moving card type, a single row of brushes usually suffices to completely analyze each card, these brushes, of course, searching the several index point positions at differential times and differentially controlling the adding and printing mechanism to enter items therein according 50 to the differential time at which the circuit is made at the analyzing brushes. The automatic group control system usually consists of a circuit including the two sets of analyzing brushes 55 in series and if the cards under the two sets of

brushes contain identical controlling perforations, this circuit would be closed at some time in the machine cycle, serving to keep the card feed active to feed another card during the succeeding card feeding cycle. If the controlling perforations are not identical in successive cards, this series circuit fails to make and the machine either stops or automatically takes a total of the data entered into the accumulators. 5

For certain classes of work, the existing forms 10 of automatic group control mechanism cannot be satisfactorily employed and it is accordingly the principal object of the present invention to provide an automatic group control mechanism for a tabulating machine, which is designed to 15 respond to more varied conditions than control systems at present.

In existing systems, where, for example, six 20 columns are utilized for operation of the automatic group control mechanism, the successful 25 operation of the device is predicated upon the presence of one or more perforations in each of the six columns, since a series circuit must be completed through each columnar position in order to continue the machine in operation. The 30 present system permits the absence of perforations in one or more of the card columns included in the control field. Such field may contain perforations representing the name of a 35 town or account number where the name of the town or the account number may consist of two 40 separate words or numbers with a space between represented by a column left blank. On successive cards, the position of the blank columns may vary, especially in the case of names of 45 towns where the number of control columns is determined by the name of the town having the greatest length, so that where a shorter name is recorded, there will be numerous blank columns 50 included in the control field of the card.

In carrying out the object of the invention, there are provided a pair of relays for each possible control column. One relay of each pair is controlled from one of the analyzing stations and the other of each pair is controlled from the second analyzing station. Between each of the pair of relays is a normally open circuit path which is completed if one of the pair of relays is energized in response to a perforation sensed at one analyzing station without accompanying energization of the other of the pair. The completion 55 of the normally open circuit indicates a non-comparison of a card column and causes interruption of card feeding operations.

A further object of the invention resides in the 55

provision of an automatic group control mechanism in which all of the index point positions of the same value are analyzed and tested for agreement before the index point positions of the next value are analyzed.

Various other objects and advantages of the invention will be obvious from the following particular description of one form of mechanism embodying the invention or from an inspection 10 of the accompanying drawings; and the invention also constitutes certain new and useful features of construction and combination of parts hereinafter set forth and claimed.

In the drawings:

15 Fig. 1 is a wiring diagram of the electric circuits of a complete tabulating machine, including the improved group control circuits.

Fig. 2 is a representation of a record card showing the manner in which a controlling field 20 may be perforated.

Fig. 3 is a timing chart showing diagrammatically the relative timing of the pertinent electrical devices of the machine.

Fig. 4 is a timing chart of a modified arrangement of certain of the contact devices relating to a modified form of the invention.

The present improved system is applicable to existing machines operating either on stationary or moving cards and in connection with single 30 or combinational hole systems. It has been shown as applied to a machine of the type in which single or multiple index point positions are perforated in the card columns and in which the cards are adapted to be analyzed while in 35 motion. The particular type of machine does not enter into the present invention as any other type of machine in which single or combinational hole cards are analyzed at rest or in motion would serve the purpose of explanation and embodiment equally as well. Reference may be had to the copending application of A. W. Mills, Serial No. 634,454, filed September 23, 1932, (now Patent No. 2,079,418) for a machine of the type to which the present invention is particularly 45 adaptable.

Referring now to the drawings, the machine is provided with a card feed clutch magnet 10, shown in the upper part of Fig. 1, which, when energized, will cause the feeding of record cards 50 from the supply magazine so that they will move past the upper brushes UB and exactly one machine cycle later past the lower brushes LB. The machine is driven by the motor M, which is placed in operation by closing the switch S. Depression of the start key to close contacts 11 will complete a circuit from one side of line 12, through contacts 11, card feed clutch magnet 10, relay contacts M1a, stop key contacts 13, to line 14. In parallel with clutch magnet 10 is a 55 relay magnet R5, which is energized concurrently therewith to close a pair of contacts R5a.

As the cards subsequently pass the lower brushes LB the usual card lever contacts LCL close to complete a circuit through card lever 60 relay LCLM, which will close its contacts LCLMa, providing the holding circuit for the relay extending from line 12, to relay LCLM, contacts LCLMa, cam contacts CF1, to line 14.

It may be pointed out at this time that in 65 the circuit diagram are shown various cam controlled contacts. Those designated with the prefix are in operation when the card feeding mechanism functions; those prefixed CB are constantly in operation; and those prefixed P operate only during the functioning of the total taking

mechanism. Relay magnet LCLM closes its contacts LCLMb to provide a holding circuit for the card feed clutch magnet which is traceable from line 12, contacts LCLMb, R5a, magnet 10, contacts M1a, contacts 13, to line 14. As long as the successively fed cards contain the same classification or group control designations, the circuit just traced will remain established and cards will continue feeding. Upon a change in group classification, the group control mechanism will 10 function to energize the relay M1, thereby opening its contacts M1a to permit interruption of the card feed clutch magnet circuit when cam contacts CF12, which normally short circuit contacts M1a, open at a predetermined point in the 15 cycle of operations. The group control mechanism is shown in the central part of Fig. 1 and comprises a set of relays having windings 17 and 18 and a second set of relays having windings 19 and 20. The two sets of relays are arranged in pairs and three such pairs have been shown in the circuit diagram for control by three card columns, although it will be understood that a great many more are usually provided, the number generally being about sixteen. 20

The windings 18 are provided with plug sockets 21 which are connected by suitable plug connections 22 to the brushes LB which traverse the columns containing the control designations. The windings 19 are provided with sockets 23 which are connected through plug connections 24 to the upper brushes UB which traverse the same card columns. Associated with windings 17 are contacts 17b, 17c, whose common contact blades are connected to plug sockets 25, which are interconnected by connections 26, as shown, when all three orders are utilized. A further plug connection 27 is made from one of the sockets 25 to a plug socket 28 which is wired to a winding of a relay magnet 29. As the record card moves past the brushes, circuits will be completed through the windings 19 at times corresponding to the location of the perforation in the columns under consideration. Assuming a perforation in the "9" index point position of the column traversed by the brush associated with the uppermost winding 19, the particular circuit will be traced as follows: from line 12, through cam contacts CB1, contacts CF11, common contact roller, perforation in the "9" index point position, brush UB, plug connection 24, to socket 23 of the uppermost winding 19, wire 30, card lever relay contacts UCLMa, closed while cards are passing the upper brushes, to line 14. Energization of winding 19 will close contacts 20a, establishing a circuit through winding 20 traceable from line 12, through wire 32, winding 20, contacts 20a, wire 33, cam contacts CF30, to line 14. Energization of windings 19 and 20 will cause opening of the contacts 20c and closure of contacts 20b.

The card lever relay contacts UCLMa are controlled by relay magnet UCLM connected to a so-called card lever brush 31 which traverses the edge of the cards. When the brush 31 is not insulated from the contact roller by the presence of a card thereat, a circuit is completed from line 12, contacts CB1, CF11, contact roller, brush 31, contacts CF9, relay UCLM to line 14. Relay UCLM closes its contacts UCLMb to establish a holding circuit through contacts CF8. The time of energization and holding of relay UCLM is indicated on the timing chart. Thus, as long as cards continue to feed, relay UCLM is not energized and its contacts UCLMa consequently remain closed.

If, while the perforation sensed by the upper brushes completes the circuits energizing windings 19 and 20 a correspondingly located perforation is sensed by the corresponding lower brush, a circuit will be completed traceable from line 14, lower card lever contacts LCLMc, cam contacts CF2, lower brush common contact roll, perforation in the card, plug connection 22, to socket 21, uppermost winding 18, wire 34, cam contacts CB1, to line 12. Winding 18 closes contacts 17a to provide a circuit for winding 17 which is traceable from line 12, wire 32, winding 17, contacts 17a, wire 33, contacts CF30, to line 14. The consequent energization of winding 17 will open contacts 17c and close contacts 17b. If windings 19 and 18 are not currently energized; that is, if the cards at the upper and lower brushes do not have a perforation in the same index point position, one of the contacts 20c or 17c will fail to open.

Assuming that winding 19 is energized without accompanying energization of winding 18, accordingly contacts 20b will be closed and contacts 17b and 17c will remain in the position shown. A circuit will accordingly be thereupon traceable from line 14, cam contacts CB17, wire 35, contacts 20b, contacts 17c, plug socket 25, connection 27, socket 28, right hand winding of magnet 29, to line 12. Magnet 29 will close its contacts 29a to provide a holding circuit from line 12, left hand winding of magnet 29, contacts 29a to cam contacts CB24, to line 14. Energization of magnet 29 will cause interruption of card feeding through further circuits to be traced hereinafter.

If winding 18 had been energized without accompanying energization of winding 19, the circuit through magnet 29 would have been completed through a path including contacts 17b and 20c. It will be noted that the circuit to magnet 29 is not completed when windings 19 and 18 are both deenergized or both energized and that each order of the control mechanism represented by pairs of windings 19 and 18 control parallel circuits independent of one another. For example, if the disagreement in control occurred in the lowermost order, the circuit from wire 35 would extend through either of the lowermost contacts 20b or 20c, thence through either of the lowermost contacts 17b or 17c, to the lowermost socket 25, thence through connections 26 and 27 to magnet 29. Referring to the timing chart, it will be seen that the cam contacts CB1 close and open again for each index point position of the card and that the cam contacts CF30 maintain the holding circuit for the windings until index point positions "9" to "1", inclusive, have been analyzed.

At this time, contacts CF30 open to drop the holding circuits, permitting restoration of all the relay contacts 17a to 17c and 20a to 20c. Thus, the subsequent analysis of the index point positions "11" and "12" will take place to determine whether perforations in these positions are in agreement on the two cards traversing the analyzing brushes. In accordance with the system of designating alphabetic data by combinational hole perforations in card columns, characters are represented in the card either by a single hole in one of the index point positions or by two perforations in a column, one of which is made in the positions "9" to "1" and the second in the positions "0", "11" or "12", so that where combinational hole data are analyzed, the only possible combinations are the perforation

in the "0", "11" or "12" position plus a perforation in one of the digit positions. For this reason, the holding circuit for the windings 17 and 20 which is controlled through cam contacts CF30 is maintained throughout the portion of the cycle 5 during which the digit positions are analyzed.

It will be appreciated that where a different combinational arrangement of holes is employed, for example, where any two or more positions in a column may be perforated, the cam contacts 10 CF30 may be arranged to break for each position sensed.

The cam contacts CB17, as shown on the circuit diagram, make for each index point position 9-1, 11 and 12 sensed and it will be observed 15 that the making of contacts CB17 occurs shortly after each position has been sensed and it will be apparent that for each index position sensed there will be a separate and distinct testing operation upon the closure of the contacts CB17. 20

It will be noted that contacts CB17 and CF30 are open when the "0" index point positions are sensed so that no sensing circuit or testing hold circuit is provided for a "0" hole. This elimination of a "0" holding circuit for the control 25 re-lays is due to the following reason. By the process of elimination, it will be found that a "0" test is unnecessary, because if no other numerical figures are punched, the columns sensed must either be blank or contain "0's" in which case 30 there would have to be comparison. It will be noted that the shunt control holding circuit through relay 29 held by contacts CB24 is not broken for "0" but holds until after the 11 and 12 positions are sensed, in order not to lose the 35 setup effected during sensing of the digit positions 9-1.

In Fig. 4 is shown the modified timing of cam contacts CF30 which have applications in which combinational hole perforations include any two 40 or more index point positions. The repeated opening and closing of contacts CF30 in conjunction with the repeated opening and closing of contacts CB17 will bring about a repeated sequence of operations including the sensing of an 45 index point position, the setting up of a holding circuit for such relays as may be energized during the sensing in that position, the testing of the relay setting, and the breaking of the holding circuit, permitting its restoration in preparation for analysis of the next index point position.

An example will now be given of the manner in which control fields in which one or more columns are blank, are handled by the mechanism. 55 In Fig. 2 is shown a record card in which the control field embraces columns 5 to 14 and in which is perforated a representation of the name "New York" and in which column 8, representing a space between the two words, is blank, as 60 are also columns 13 and 14. In Fig. 2 it will also be noted that each of the letters is represented by a perforation in one of the digit positions and a second perforation in one of the positions "0", "11" or "12". If, as the card bearing the 65 perforations of Fig. 2 passes the lower brushes LB a similar card having the same perforations passes the upper brushes, the relay windings 18 and 19 associated with columns 5, 6, 7, 9, 10, 11 and 12 will all be energized, while the relays associated with columns 8, 13, and 14 will remain deenergized and no circuit will be completed to relay magnet 29. Thus where blank columns are included in the controlling field, such blank columns do not effect the status of their related 75

relays 18 and 19 and of themselves are ineffective to interrupt card feed unless there is a disagreement.

As the cards pass their respective sets of 5 brushes, the relay magnets 18 and 19 will become deenergized after the "1" index point positions have been analyzed and will be re-energized in response to the perforations in the "11" and "12" positions.

10 It will now be explained in what manner the energization of magnet 29 interrupts the further card feeding operations and initiates total taking operations. Upon energization, magnet 29 closes a pair of relay contacts 29b, which permit 15 completion of a circuit upon closure of cam contacts CF1, which is traceable from line 14, contacts LCLMc, contacts CF1, contacts 29b, switch 36, left hand coil of the relay magnet MI, cam contacts CB19, to line 12. Magnet MI will close 20 its contacts MIb, establishing a holding circuit from line 12, through right hand winding of magnet MI, contacts MIb, cam contacts PM8, to line 14. Contacts PM8 are normally closed and open 25 during a total taking cycle of operations so that once magnet MI is energized, it remains so until total taking operations have been performed. The magnet opens its contacts MIa, shown at the top of Fig. 1, so that upon opening of cam contacts CF12 during the latter half of the last card feed 30 cycle, the card feed clutch circuit will be interrupted.

Magnet MI closes its contacts MIc and MID, the former of which permits the completion of a circuit from line 12, through cam contacts CB21, 35 switch 37, contacts MIc, print controlling magnet PCM, to line 14. Energization of magnet PCM will cause operation of the printing mechanism during the ensuing total taking cycle.

Closure of contacts MID will complete a circuit 40 extending from switch 37, through contacts MID to a magnet TS to line 14. The magnet TS prepares the circuits of the machine for recording the total standing in the accumulators. The detailed manner in which these magnets control 45 the various operations form no part of the present invention and their detailed functions need accordingly not be described herein. The magnets PCM and TS correspond to the similarly designated magnets in the application referred 50 to. The circuits for the accumulating and printing devices are generally indicated at the bottom of Fig. 1 where three denominational orders of an accumulator are diagrammatically represented and in which 42 indicates the usual printing magnets, 43 the adding magnets, and 44 the subtracting magnets.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It 65 is the intention, therefore, to be limited only as indicated by the scope of the following claims.

What is claimed is as follows:

1. In a group control system for a tabulating machine responsive to record cards having 70 columns of differently located index point positions, comprising a pair of sensing devices for sensing a column in each of a pair of record cards, one sensing device sensing the different positions in the column of one card, in succession, while 75 the other sensing device, concurrently, and in a

like manner senses the correspondingly located positions in the column of the second card, a magnet for each sensing device, circuit connections completed by each sensing device upon sensing a perforation in an index point position for energizing its related magnet, means controlled by each magnet, upon energization, for completing a holding circuit for the magnet, an armature for each magnet, a control magnet, a circuit closing device, a pair of normally incomplete circuit 10 connections including said armatures intermediate the control magnet and the circuit closing device, said armatures and circuit connections being arranged to complete one of said intermediate connections when only one of the related magnets is energized, in response to the concurrent sensing of the same index point positions in the two card columns, and means for operating said circuit closing device to complete a circuit through said control magnet and the 20 completed intermediate connection, said means being coordinated with said sensing devices for effecting closing of said circuit closing device after an index point position is sensed; a related magnet energized and a holding circuit completed 25 therefore, and for effecting reopening of said circuit closing device before the next succeeding index point position is sensed.

2. The invention set forth in claim 1 in which a pair of normally closed contacts is included in 30 said holding circuit and means are provided to enable opening of said contacts for rendering the holding circuit ineffective, said means being coordinated with said sensing devices for effecting opening of said contacts upon the completion of sensing of a predetermined succession of 35 index point positions less than the total number thereof and for effecting reclosing of said contacts before all of the index point positions are sensed.

3. The invention set forth in claim 1 in which a pair of normally closed contacts is included in 40 said holding circuit and means are provided to enable opening of said contacts for rendering the holding circuit ineffective, said means being 45 coordinated with said sensing devices for effecting opening of said contacts after the said circuit closing device has been operated and again effecting reclosing of said contacts before the next succeeding index point position is sensed. 50

4. In a group control system for a tabulating machine, a card sensing device for sensing a column of a card for perforations in differentially located index point positions representing the numbers 9, 8, 7, 6, 5, 4, 3, 2, 1, 0, 11 and 12 in 55 succession a second card sensing device for concurrently sensing a column of another card for correspondingly located perforations, a pair of relay magnets, one for each sensing device and each energized through a circuit connection established by its related sensing device upon sensing a perforation in a card column, circuit connections for each magnet established upon energization of the magnet to hold the same energized, a pair of contacts in said circuit connections, controlling means therefor to effect continued closure of said contacts during the sensing of the positions representing the numbers 9, 8, 7, 6, 5, 4, 3, 2 and 1, opening of the contacts during the sensing of the position representing 0 70 and reclosure during the sensing of the positions representing 11 and 12, an armature for each relay magnet, a control magnet, a circuit closing device, a pair of normally incomplete circuit connections including said armatures and inter- 75

mediate the control magnet and the circuit closing device, said armatures being arranged to complete one of said intermediate connections when only one of the related magnets is energized, in response to the concurrent sensing of the same index point positions in the two card columns, and means for operating said circuit closing device to complete a circuit through said

control magnet and the completed intermediate connection, said means being coordinated with said sensing devices for completing said circuit and again opening it after each one of the index point positions 9, 8, 7, 6, 5, 4, 3, 2, 1, 11 and 12 ⁵ is sensed.

EDWARD J. RABENDA.
